INVENTOR,
Erhard Allen,
BY Honora S. Smith,
His ATTORNEY.

UNITED STATES PATENT OFFICE.

ERHARD ALLEN, OF DAYTON, OHIO, ASSIGNOR TO THE DAYTON DISPLAY FIXTURE COMPANY, OF DAYTON, OHIO, A CORPORATION OF OHIO.

DISPLAY RACK.

1,411,553.

Specification of Letters Patent. Patented Apr. 4, 1922.

Application filed May 21, 1921. Serial No. 471,400.

To all whom it may concern:

Be it known that I, ERHARD ALLEN, a citizen of the United States, residing at Dayton, in the county of Montgomery and 5 State of Ohio, have invented certain new and useful Improvements in Display Racks, of which the following is a specification.

The principal object of my invention is to provide for a display rack, means for 10 making a basket, box, bin or shelf holder easily attachable to, and readily removable from, the rack. These means make it possible to get the rack through a small doorway, as well as to place the rack in a smaller 15 crate for shipment. They also make it possible for the user to easily substitute in the rack, a holder or shelf of one type for that of another type to receive boxes, baskets or the articles themselves.

Other important and incidental objects 20 will be brought out in the following specification, and particularly set forth in the subjoined claims.

In the accompanying drawings, Figure 25 1 is a front view of a display rack equipped with my improved detachable combination box and basket holder. Figure 2 is an end view of the rack, with the combination box and basket holder removed to show one of 30 the notched supporting members for the latter. Figure 3 is a plan view of one of the combination box and basket holders provided with my improved supporting spacers. Figure 4 is a cross sectional view taken on 35 the line 4—4 of Figure 3, showing how the spacers are received by the notches in the arched supporting members on the rack. And Figure 5 is a longitudinal sectional view of one of the spacers, taken on the 40 line 5—5 of Figure 3.

Throughout the specification and drawings, similar reference characters denote corresponding parts.

Referring to the accompanying drawings, 45 the numeral 1 designates a base or spider supported upon rollers 2. Projecting upwardly from the spider 1 are standards 3, 3 that support a tray 4.

Transversely mounted on said spider 1, 50 and extending from the front to the rear portion thereof, are two arch shaped supporting members 5, 5. Provided in the front top portion of each arch shaped member 5, are two hook-shaped notches 6, 6, 55 while in the rear top portion of each arch

shaped member 5 are two hook-shaped notches 7, 7 that are inclined in the opposite direction. (See Figures 2 and 4.)

Adapted to be supported upon each side of the display rack, by the notched arch shaped members 5, 5, is a combined box and basket holder which is constructed as follows. Connected between two end members 8, 8 is a front angle member 9 and a rear longitudinal member 10 which form together a rectangular box receiving frame. When boxes are mounted upon the latter, the upwardly projecting flange of the angle member 9 serves to hold them on said frame. (See Figures 3 and 4.)

Dividing the frame just described into basket receiving spaces, are pairs of downwardly turned angle irons 11, 11. Between these pairs of angle irons 11, 11 are secured basket receiving ring members 12, each of 75 which is adapted to support a basket when the space above it is not occupied by a box. (See Figures 1 and 2.)

For the purpose of securing these combined box and basket holders to the display 80 rack in such a manner that they may be readily removed therefrom, the two end pairs of angle irons 11, 11 are disposed a short distance apart by spacers 13. Referring to Figure 5, each spacer is a cylindrical 85 piece of metal which is turned down at its middle and end portions to leave between its reduced middle part and each end part a large flanged portion 14. The reduced ends of each spacer are secured in holes in the 90 downwardly projecting portions of each pair of angle irons 11, 11 which are held apart by the flanged portions 14, 14 of the spacer. These spacers are so disposed between the 95 angle irons 11, 11 that their reduced middle portions may enter the notches in the arch shaped members 5 on the display rack. Accordingly, when it is desired to mount one of the combination box and basket holders upon the front portion of the rack, the 100 holder is brought to a position to permit the reduced middle portions of its spacers 13, 13 to enter the notches 6, 6 respectively in each arch shaped member 5, by which it will be supported in an inclined position, as shown 105 in Figure 4. In a like manner the reduced middle portions of the spacers 13 of the rear box and basket holder will enter the notches 7, 7 in the arch shaped members 5, 5 for support by the latter. When it is 110

desired to remove either one, or both, of the box and basket holders, it is only necessary to withdraw the reduced middle portions of the spacers 13 from the notches that 5 receive them in the arch shaped members 5, whereupon the holder may be easily lifted from the rack to permit the latter to be moved through a narrow doorway or shipped in a small crate. After it is thus moved 10 or shipped, the user can easily reattach the holders to the arch shaped members 5 by inserting the middle portions of their spacers 13 in the notches of said members.

I do not wish to be limited to the details 15 of construction and arrangement herein shown and described, and any changes or modifications may be made therein within the scope of the subjoined claims.

Having described my invention, I claim:
20 1. In a display rack, the combination with
a base, of arch-shaped supporting members

mounted upon said base, having notches in their top portions, a supporting frame, transverse members disposed in pairs in said frame, and spacing elements between 25 the transverse members of each pair, adapted to enter the notches in the arch-shaped members.

2. In a display rack, the combination with a base, of arch-shaped supporting members 30 mounted upon said base, having notches in their top portions, a supporting frame, transverse members disposed in pairs in said frame, and spacing elements between the 35 transverse members of each pair, having reduced middle portions adapted to enter the notches in the arch-shaped members.

In testimony whereof I have hereunto set my hand this 19th day of May, 1921.

ERHARD ALLEN.

Witness:

HOWARD S. SMITH.
